UNITED STATES PATENT OFFICE.

ALLEN K. BISHOP, OF FORSYTH, MISSOURI.

COMBINED HAY RAKE AND LOADER.

1,043,563.

Specification of Letters Patent.

Patented Nov. 5, 1912.

Application filed October 26, 1909, Serial No. 524,656. Renewed July 3, 1912. Serial No. 707,607.

To all whom it may concern:

Be it known that I, ALLEN K. BISHOP, a citizen of the United States, residing at Forsyth, in the county of Taney and State of Missouri, have invented certain new and useful Improvements in Combined Hay Rakes and Loaders, of which the following is a specification.

My invention relates to improvements in combined hay-rakes and loaders; and it consists of the novel features of construction and combinations of parts hereinafter described and claimed.

The object of my invention is to provide a simple and practical machine of this character which will rake the hay, grass or the like from the field and then deliver it to a baling chamber wherein it is automatically compressed and baled.

The above and other objects of the invention, as will hereinafter appear, are attained in the preferred embodiment of my invention, illustrated in the accompanying drawings, in which:

Figure 1 is a side elevation of the machine; Fig. 2 is a top plan view; Fig. 3 is a vertical longitudinal section; Figs. 4 and 5 are cross sectional views; and Figs. 6 and 7 are detail views.

Referring more particularly to the drawings, 1 denotes a suitable body or main frame mounted at its front end upon two supporting and driving wheels 2, and at its rear end on steering wheels 3. The latter are journaled on a pivoted axle 4 provided with a well known form of steering gear 5 arranged within convenient reach of the driver who occupies a seat 6 at the rear end of the body 1.

The wheels 2 are loose upon ends of the lower section 7 of a two part front axle, the upper section or part 8 of which is secured by fastening devices consisting of opposing clamp plates 9 united by U-bolts 10 provided with upwardly and forwardly projecting portions to serve as pivots for a vertically tilting rake platform 11. The axle is made in two parts or sections to give it greater strength and to facilitate the mounting of the swinging frame carrying the platform. The rake platform is suitably secured to a frame formed preferably of two longitudinally-extending bent or L-shaped bars 12 having the upper or offset pivotal portions of the bolts 10 arranged in the intermediate portions of their short upwardly

projecting arms. These short arms are united by a connecting bar or rod 13 and the long diverging front arms or ends of the bars 12 are united by two parallel bars 60 or rods 14, 15. These rods 14, 15 have mounted upon them rake teeth 16 which form a rake equal in width to the machine, and the projecting extremities of the rod 15 have journaled upon them small ground 65 wheels 17 to relieve the rake teeth of the weight of the platform and the parts thereon. The rake platform is tilted or adjusted vertically by means of block and tackle 18 arranged between the upper rear ends of 70 the bars 12 and the side portions of the body or main frame 1, and having the cables 19 extending rearwardly under suitable guides and wound upon a windlass 20 mounted beneath the rear portion of the body. The 75 shaft of the windlass 20 is connected by beveled gears 21 to an upwardly and rearwardly inclined operating shaft 22 carrying a hand wheel arranged within convenient reach of the driver. 80

Arranged upon the intermediate portion of the main frame or body 1 is a bale box or chamber 23 within which reciprocates a plunger 24. Said plunger is connected to one end of a pitman 25, the other end of 85 which is connected to a wrist pin 26 between two crank disks 27 on the opposing inner ends of a two part shaft 28 journaled in suitable bearings on the front portion of the main frame or body 1 adjacent the front 90 axle. The crank shaft 28 has at its outer ends loosely mounted pinions 29 adapted to be locked to said shaft for rotation therewith by suitable clutches 30 and adapted to mesh with gears 31 fixed to the inner portions of the wheels 2. 95

The rear portion of the press or bale chamber may have its upper part vertically movable so that it may be adjusted by means of a tension screw 32 for the purpose of varying the density or compactness of the bale. This upper and rear portion of the bale chamber 23 is also provided with an improved automatically operating head block dropping mechanism consisting of an 100 upright elongated tubular guide and support 33 adapted to receive one of the head blocks 34 and arranged in the top of the chamber 23 immediately in rear of an inlet hopper 35 on said chamber. The head block 34 is maintained in elevated position 105 in its guide 33 by a longitudinal slide 36 on

the forward end of which said head block is adapted to rest. A spring or springs 37 maintain the slide 36 in forwardly projected position but it is adapted to be automatically retracted by engagement of lateral lugs or projections 38 on the opposite sides of a wheel 39 with upstanding lugs or projections 40 upon the rear portion of said slide. The wheel 39 is arranged on a transverse shaft 41 suitably journaled on the rear portion of the bale chamber so that the periphery of said wheel 39 is adapted to project into the space within the bale chamber and to be engaged and actuated by a bale forced therethrough. Owing to this construction it will be seen that as a bale is formed and forced through the rear portion of the bale chamber, the wheel 39 will be caused to rotate once by reason of its contact with such bale so that when the lug or lugs 38 upon the wheel engage the lug or lugs on the slide, said slide will be retracted against the tension of the springs 37 to permit the head block 34 to drop into the bale chamber.

The press or baler is provided with an automatically operating force feed mechanism consisting of a packing head or plunger 42 on the lower ends of two upright rods 43 depending from the intermediate portion of a horizontal bar 44 fixed intermediate the ends of two upright slide rods 45. The upper ends of the slide rods 45 are guided by the upper cross piece of an upright inverted U-shaped frame 46 rising from the intermediate portion of the main frame or body 1. The lower ends of the slide rods 45 have connected to them the lower ends of coil springs 47, the upper ends of which latter are attached to the upper portion of the frame 46. These springs 47 elevate the packing head 42 and the latter is adapted to be depressed by operatively connecting it to the press plunger 24. This operative connection consists of chains or the like 48 passed around guide pulleys 49 and having their upper ends connected to the lower extremities of the slide rods 45, and the opposite ends of said chains are connected to a cross rod 50 carried by the plunger. Owing to this construction it will be seen that as the plunger is retracted from beneath the hopper of the bale chamber the packing head 42 will be forced down through said hopper to feed the hay or other material into the chamber in advance of the plunger.

The hay, straw or the like, that is raked on to the platform 11 by the rake teeth 16 is directed on to a centrally and longitudinally disposed elevating mechanism which discharges it into the hopper of the bale chamber. This elevator mechanism is of considerably less width than the rake platform, and for the purpose of directing the

hay gathered upon the side portions of said platform on to the elevator, horizontally disposed rotary feeding devices or rakes are arranged on the platform on opposite sides of the lower portion of the elevator and immediately in rear of the relatively stationary rake 16. These rotary raking or feeding devices are similar and hence a description of one will suffice for both. Each consists of an upright shaft 51 suitably journaled in the platform and having at its upper end a head 52 provided with radiating arms 53 carrying plates 54 (see Fig. 5). Pivotedly connected to the latter are rake members 55 which are yieldably mounted by means of springs 56. When the shaft 51 is rotated it will be noted that the rake members 55 will brush the hay on to the lower portion of the elevator. The lower ends of the shafts 51 are connected by beveled gears 57 to transverse shafts 58 journaled in suitable bearings beneath the rake platform 11 and having upon their outer ends sprocket wheels 59. The latter are connected by chains 60 to sprocket wheels 61 fixed upon the outer portions of the wheels 2, the rotary raking or feeding devices being thus driven from said wheels.

The elevating mechanism consists of a series of endless belts of usual form and construction, the preferred arrangement consisting of a short belt or apron 62 arranged in a central opening in the rake platform 11 and adapted to discharge upon an upwardly and rearwardly inclined belt or apron 63 above which latter is a superposed belt or apron 64 to provide a force feed for the hay. The upper end of the elevator belt or apron 63 discharges upon the downwardly and rearwardly inclined belt or apron 65, which latter in turn discharges into the hopper 35 of the press or bale chamber. These belts or aprons are arranged in a suitable supporting framework 66 and are driven by sprocket chain gearing 67 arranged on one side of said frame and including a sprocket wheel or gear on a transverse shaft 68 journaled in suitable bearings beneath the rake platform 11. The outer end of the shaft 68 has upon it a sprocket wheel 69 which meshes with one of the sprocket chains 60.

While the machine may be pulled, pushed or propelled by any suitable means, I preferably provide beneath the intermediate or rear portion of the main body 1 a transverse pivoted draft bar 70 to the ends of which are attached double trees 71 for draft animals.

72 denotes a suitable receptacle supported on the intermediate portion of the body for holding head blocks etc., and 73 denotes a longitudinal tray or receptacle similarly supported for holding bale fastening wires.

Having thus described the invention what is claimed is:

1. The combination of a supporting frame, a rake platform carried thereby and having side portions separated by a central opening, a rake on the front edge of the platform, an elevating means in said central opening in the platform, vertical shafts extending through the side portions of the platform, driving means at the lower ends of the shafts, hubs on said vertical shafts, arms radiating from the hubs and spring-pressed rake members pivoted to and depending from said arms and adapted to sweep across the side portions of the platform and throw the hay from the end portions of the rake onto the elevating means.

2. The combination of a rake, an elevator, and a rotary raking device having a vertical axis and radiating arms carrying depending, spring-pressed, pivotally-mounted rake members, said device being arranged in rear of one end portion of the rake to sweep the hay onto the elevator.

25 3. The combination of a supporting frame, an axle composed of upper and lower sections, clips uniting said axle sections and formed with pivots, ground wheels mounted on one of the axle sections, a rake platform 30 consisting of two longitudinally extending bent bars and a plate formed with a central opening which leaves two side portions, each of said bent bars having forwardly diverging ends secured beneath the side portions 35 of the platform plate and upwardly extending rear ends mounted on said pivots, means connected to the upper extremities of said bars for raising and lowering the platform, a rake extending across the front end of the 40 platform, an elevator arranged in the central opening in the platform, and rotary raking devices arranged above the side portions of the platform.

4. The combination of a supporting 45 frame, an axle composed of upper and lower sections, clips uniting said axle sections and formed with pivots, ground wheels mounted on one of the axle sections, a rake platform consisting of two longitudinally extending 50 bent bars and a plate formed with a central opening which leaves two side portions, each of said bent bars having forwardly diverging ends secured beneath the side portions 55 of the platform plate and upwardly extending rear ends mounted on said pivots,

means connected to the upper extremities of said bars for raising and lowering the platform, a rake extending across the front edge of the platform, an elevator arranged in the central opening in the platform, rotary 60 raking devices arranged centrally on the side portions of the platform having vertical shafts extending through said platform, transverse shafts beneath the side portions of the platform and geared to said vertical 65 shafts, sprocket chain gearing between the outer ends of said transverse shafts and said ground wheels, and means for driving said elevator from the sprocket chain gearing on one side of the platform. 70

5. The combination of a supporting frame, steering wheels arranged at the rear thereof, a stationary front axle arranged transversely at the front end of the frame and composed of upper and lower sections, 75 clips uniting said sections and formed with pivots, ground wheels mounted on one of the axle sections, a rake platform consisting of two longitudinally extending bent bars and a plate formed with a central opening which leaves two side portions, each of said bent bars having forwardly diverging ends secured beneath the side portions of the platform plate and upwardly extending rear ends mounted on said pivots, block and 80 tackle between the upper ends of said bars and said frame for raising and lowering the platform, a rake secured rigidly across the front edge of the platform, supporting wheels at the ends of said rake for supporting the same and the lower front end of the platform, an endless elevator arranged in the central opening in the platform, vertical shafts extending through the side portions of the platform, rotary raking devices upon 85 the upper ends of said vertical shafts, transverse shafts arranged beneath the side portions of the platform and geared to said vertical shafts, sprocket chain gearing between the outer ends of said transverse 90 shafts and said ground wheels and means for driving said elevator from the sprocket chain gearing on one side of the platform. 95

In testimony whereof I affix my signature in presence of two witnesses.

ALLEN K. BISHOP.
